GRINDING MACHINE

Herbert Vanderbeek, Canton, Ohio, assignor to
 The Timken Roller Bearing Company, Canton,
 Ohio, a corporation of Ohio

Application October 5, 1934, Serial No. 746,961

3 Claims. (Cl. 51—134)

This invention relates to grinding machines, particularly automatic grinding machines of the multiple spindle type for grinding the ends of rolls for roller bearings.

5 The principal object of the present invention is to provide a grinding machine of the above type that will give the ends of the rolls a spherical shape; to provide for positioning the roll spindles longitudinally of the turret so that a given 10 amount of stock will be removed from each roll; to provide for maintaining the spindles in such position; to provide for rotating the spindles when the rolls carried thereby are in engagement with the grinding wheel; to provide for the angular 15 adjustment of the grinding wheel with reference to the roll to be ground; and to provide for automatically dressing the grinding wheel. The invention consists in the grinding machine and in the construction, combinations and arrangements of parts hereinafter described and 20 claimed.

In the accompanying drawings, which form part of this specification and wherein like symbols refer to like parts wherever they occur,

25 Fig. 1 is a view, partly in plan and partly in horizontal section, of a grinding machine embodying my invention,

Fig. 2 is a side elevational view of the machine, Fig. 3 is an end elevation thereof,

30 Fig. 4 is a vertical longitudinal section through the spindle turret on the line 4—4 in Fig. 1,

Fig. 5 is a vertical transverse section on the line 5—5 in Fig. 4,

Fig. 6 is a fragmentary vertical section through 35 the upper and lower spindles of Fig. 4 (enlarged).

Fig. 7 is a fragmentary section through the turret, showing the tool for dressing the grinding wheel; and

Fig. 8 is an enlarged diagrammatic view illustrating the cooperating portions of the grinding 40 wheel and roll end.

The grinding machine shown in the accompanying drawings is especially adapted to form or grind a spherical surface on the large end of a 45 conical antifriction bearing roll 1. In the type of conical bearing roll shown, such surface is in the form of a convex spherical band or annular land 2 which has a relatively large radius of curvature and is located between a radiused edge 50 3 of the large end of the roll and a circular depression 4 therein.

Said machine comprises a housing 5 supported on a suitable table 6 and provided with an upright frame 7 in which a multiple spindle turret 55 8 is supported for rotation on a horizontal axis.

Said turret is fixed to and rotates with a horizontal shaft 9 whose ends are journaled in suitable antifriction bearings 10 mounted in the corresponding ends of the upright frame 7.

The mechanism for rotating the turret 8 comprises an electric motor 11 mounted on a bracket 12 secured to the side of the housing 5, a belt 13 and pulley connection 13 between said motor and a horizontal shaft 14 extending longitudinally of said housing, and a worm gearing connection 15 10 between the shaft 14 and a horizontal cross-shaft 16 journaled in said housing and provided with a worm 17 meshing with a worm gear ring 18 fixed to said turret.

The rotary turret 8 has a plurality of circum-

ferentially spaced roll holding spindles mounted parallel to the axis thereof for rotary and axial sliding movement therein. Each of these roll spindles comprises a hollow cylindrical body member 19 supported at its ends for rotary and axial sliding movement in bearings provided

therefor in outstanding annular flanges 20 at the corresponding ends of the turret 8. The front end of the body member 19 of each roll spindle is provided with a suitable roll holding chuck or collet 21 that is removably secured to said spindle by means of a threaded cap 22. The body member 19 of each spindle is provided with a journal in the form of a bronze bushing or sleeve 19a which fits within the bearing provided there-

25 for in the flange at the front end of the turret and is held on said body member between a nut 19b threaded thereon adjacent to the rear face of said flange and the threaded cap 22 at the feed end of said spindle. The bearing for the rear end of the body member of each spindle

20 30 35 comprises a sleeve 19c mounted with a press fit in the annular flange at the rear end of the turret end positioned and further held by means of a screw 19d.

40 Each spindle is provided with a knock-out plunger 23 comprising a rear portion, which is axially slidable in the bearing sleeve 19c in abutting relation to the rear end of said spindle and a reduced front portion that is slidable in the bore of the body member of said spindle. This knock-nut plunger is held in rearward or retracted position by means of a coil spring 24 located in the bore of the body member of the spindle between the collet 21 and a collar 25 provided therefor on said plunger. In the lower-most station or position of the spindle the knock-out plunger 23 is moved forwardly therein to eject the roll from the collet 21 thereof by means

45 50 55 of a suitable cam plate 26, which is fixed in the

55 55 55

lower portion of the turret supporting frame 7 in position to be engaged by a roller 27 carried by the rear end of said knock-out plunger.

During the rotation of the turret, the spindles 5 on the downwardly moving side of the turret are successively rotated on their own axes by means of a continuously moving endless belt 28 located on said side of said turret. The upper end of the spindle driving belt 28 is supported on a pulley 29 journaled for rotation on a horizontal axis disposed parallel to the turret and spindle axes. As shown in the drawings, the pulley 29 is journaled on the free end of an arm 30 that is pivotally supported in upstanding lugs or ears 15 31 provided therefor on the top of the turret supporting frame 7. The pulley supporting arm 30 may be raised and lowered to adjust the tension of the belt 28 by means of a screw 32, which is threaded through a laterally extending lug 33 20 on the turret supporting frame 7 and bears against the underside of the free end of said arm. The lower end of the spindle driving belt 28 operates with a pulley 34 that is fixed to the inner end of the main drive shaft 14 of the turret 25 rotating mechanism. The spindle driving belt 28 is positioned so that its upward moving stretch runs between the end flanges 20 of the turret 8 on the downwardly moving side thereof; and each spindle is provided between said end flanges with 30 a pulley 35 adapted, once during every revolution of said turret, to engage said belt stretch and be driven thereby while in contact therewith.

As each spindle on the upwardly moving side of the rotating turret reaches a horizontal plane 35 passing through the turret and spindle axes a roll is inserted in the collet 21 of the spindle by means of a suitable roll feeding and positioning mechanism. Said mechanism comprises a hopper 36, into which the rolls to be end ground are dumped, a tube 37 for transferring said rolls from the hopper to a suitable turning roll box 38 where they are automatically positioned with their small ends down, and a tube 39 for transferring the rolls thus positioned from the turning box to a suitable loading device 40, which inserts a roll into the collet of each spindle as it comes into position in front of the loading device.

The rolls are positioned in the collets 21 of the spindles 19 with their large ends projecting beyond the front ends thereof. In order to insure the removal of the same amount of stock from the end of each roll regardless of its size, the rolls after being inserted in the collets are successively engaged, at the limit of their upward 50 travel in the rotating turret, by a positioning wheel 41 journaled on a stud 42 fixed to the turret supporting standard or frame 7. The roll positioning wheel 41 has a beveled peripheral edge 43 and is arranged so that it contacts with 55 the projecting ends of the rolls along a vertical line as they come in position opposite said wheel. With this arrangement, if the rolls project too far beyond the collet, the positioning wheel 41 exerts an endwise pressure on the roll, thereby 60 forcing the entire spindle 19 rearwardly in the turret far enough to permit the roll to clear the positioning wheel. The spindle is frictionally held in this position by means of a plug 44 that is mounted in a radial bore in the forward end 65 flange 20 of the turret with its inner end in engagement with the sleeve 19^a of the spindle. The bushing or sleeve 19^a of the spindle is prevented from rotating therewith by a plug 44 which is held in frictional engagement with said sleeve by 70 means of a disk 46 that is seated in the outer

end of the plug receiving bore and bears against the outer end of said plug.

As stated above, the positioning wheel 41 serves to position the rolls endwise in the collets 21 so that the same amount of stock is removed from each roll. However, it is possible to dispense with the positioning wheel and grind rolls of different sizes to the same size by removing different amounts of stock from each roll according to its size.

The mechanism for forming or grinding the lands or bands 2 on the correctly positioned rolls comprises a grinding wheel 47 located on the downwardly moving side of the turret for rotation on a horizontal axis, which is disposed in a horizontal plane passing through the turret axis and is arranged at an oblique angle thereto. The roll engaging end 48 of the grinding wheel 47, which has the same spherical shape as the spherical roll end surface 2, has a radius of curvature described from the point of intersection of the turret and grinding wheel axes. The spherical grinding face 48 of the grinding wheel is generated by a dressing tool comprising a bar 49 mounted on the forward end flange 20 of the turret and having a diamond dressing point 50 on the forward end thereof in position to pass over the spherical grinding surface of the grinding wheel once during every revolution of the turret.

As shown in the drawings, the grinding wheel 47 is fixed to the forward end of the armature shaft 51 of an electric motor 52 that is mounted for longitudinal sliding movement towards and away from the turret 8 on inverted V-shaped 35 slideways 53 provided therefor on the upper surface of a plate 54 supported on the housing 5 of the machine. As shown in the drawings, the motor supporting plate 54 is movably secured to the machine by T-bolts 55, whose heads engage a 40 curved T-slot 56 provided therefor in the top of the housing, whereby the motor, together with the grinding wheel thereon, may be moved longitudinally of the arcuate T-slots to vary the angular position of the grinding wheel with respect to 45 the rolls to be ground. With this arrangement, the grinding wheel may be adjusted to bring the surface of the spherical band 2 of the roll tangent to the curved or radiused edge thereof. Suitable 50 mechanism (not shown) is provided for automatically feeding the grinding wheel in the direction of the roll in order to take up wear of the wheel due to grinding, the pressure of the grinding wheel on the roll being less than the pressure of the friction plug 44 on the roll spindle so that the position given to the spindle by the positioning wheel 41 will not be disturbed.

The operation of the machine is as follows: The rolls 1 that are to be end ground are dumped into the hopper 36 and travel down through the tube 37 into the turning box 38 where they are automatically positioned endwise and then dropped through the tube 39 into the loader 40 which inserts one of the rolls into the empty collet 21 of an upwardly moving spindle 19 when the same comes into position opposite said loader. The roll thus inserted is positioned in the collet with its large end projecting therefrom. The roll spindle with the roll therein is then carried upwardly by the rotating turret until it reaches the limit of its upward travel where it is engaged by the roll positioning wheel 41 so that a proper amount of stock will be removed therefrom by the grinding wheel. The correctly positioned roll then travels downwardly with the turret across

the downwardly moving side of the spherical grinding surface 48 of the grinding wheel 47 which forms or grinds the convex spherical band 2 on the end of the roll. During this engagement of the roll end with the grinding wheel, the pulley 35 on the roll supporting spindle moves into engagement with the upwardly moving stretch of the continuously moving endless belt 28 and thus causes the roll to rotate on its axis so as to insure uniform circumferential contact of the roll end with the grinding wheel. As the spindle carrying the finished roll moves to the lower-most station or position, the roller 27 journaled in the rear end of the knock-out plunger 23 engages the stationary cam 26, which forces said plunger forward in the direction of its collet and ejects the finished roll therefrom. The large end portion of the knock-out plunger then engages the rear end of the spindle and pushes it forward to its advance position of setting, after which the roller 27 on said plunger leaves the cam 26 and permits the spring 24 to push said plunger rearwardly out of the roll receiving portion of the collet. Another unfinished roll is then inserted in the empty collet in the manner above described and is carried upwardly by the rotating turret until the front end of the roll is engaged by positioning wheel 41, which forces the roll carrying spindle rearwardly from its advanced position of setting against the pressure of the friction plug 44 until the roll is in proper position for grinding. The pressure of the plug 44 on the sleeve 19a is sufficient to prevent the spindle from being forced rearwardly by the pressure of the grinding wheel 47 on the end of the correctly positioned roll.

The machine above described has numerous advantages. It provides automatic and accurate means for correctly positioning the rolls in the spindle collets; it provides a simple and efficient arrangement for rotating the spindles on their axes as they revolve past the rotating grinding wheel; it provides for maintaining the proper spherical shape of the grinding surface of the grinding wheel by means of the trimming device 45 which passes over the grinding surface during each revolution of the turret; and it permits the ready adjustment of the grinding wheel relative to the roll end to correctly locate the spherical land thereon. Obviously, numerous changes may be made without departing from the invention. Therefore, I do not wish to be limited to the precise construction shown and described.

What I claim is:

1. A machine for end-grinding rolls comprising a rotatable roll carrier and a rotary grinding wheel arranged with their axes substantially in the same plane and at an oblique angle to each other, said grinding wheel being located alongside of said roll carrier adjacent to the roll carrying end thereof and provided at its carrier opposing end face with a grinding surface adapted to be engaged by the end of a roll rotating with said

roll carrier, the grinding surface of said grinding wheel having a concave spherical curvature described from the point of intersection of the grinding wheel and roll carrier axes, and a tool rotatable with the roll carrier and passing over the grinding surface of the grinding wheel with each revolution of said carrier for maintaining the desired curvature of said grinding surface. 5

2. A machine for end-grinding rolls comprising a rotary turret and a rotary grinding wheel arranged with their axes substantially in the same plane and at an oblique angle to each other, a circular series of roll carrying spindles mounted in said turret for rotation therewith and on their own axes, said grinding wheel being located 10 alongside of said roll carrier adjacent to the roll carrying ends of said spindles and provided at its turret opposing end with a concave spherical grinding surface adapted to be successively engaged by the ends of the rolls in said spindles 15 as they revolve with said turret, said engagement occurring on the side of the grinding wheel nearest the turret axis and on the side of the engaged roll end remote from said axis, and means for adjusting the spindles axially in said turret to 20 correctly position the roll ends with respect to the grinding wheel before they engage the same, said means comprising a wheel journaled on said machine in position to be successively engaged 25 by the ends of the rolls in said spindles. 30

3. A machine for end-grinding roll comprising a rotary turret and a rotary grinding wheel arranged with their axes substantially in the same plane and at an oblique angle to each other, a circular series of roll carrying spindles mounted 35 in said turret for rotation therewith and on their own axes, said grinding wheel being located alongside of said roll carrier adjacent to the roll carrying ends of said spindles and provided at its turret opposing end with a concave spherical 40 grinding surface adapted to be successively engaged by the ends of the rolls in said spindles as they revolve with said turret, said engagement occurring on the side of the grinding wheel nearest the turret axis and on the side of the 45 engaged roll and remote from said axis, means for adjusting the spindles axially in said turret to correctly position the roll ends with respect to the grinding wheel before they engage the same, said means comprising a wheel journaled 50 on said machine in position to be successively engaged by the ends of the rolls in said spindles, and plugs mounted in said turret in frictional engagement with the respective spindles for maintaining them in their axially adjusted positions, the pressure of the friction plugs permitting axial movement of the spindles under the pressure of the positioning wheel but preventing such movement under the pressure of the grinding wheel. 55 60

HERBERT VANDERBEEK.
